UNITED STATES PATENT OFFICE.

HARRY M. PFLAGER, OF ST. LOUIS, MISSOURI, ASSIGNOR TO COMMONWEALTH STEEL COMPANY, OF ST. LOUIS, MISSOURI, A CORPORATION OF NEW JERSEY.

JOURNAL-BOX WEAR PLATE.

Application filed November 23, 1925. Serial No. 70,923.

My invention relates to railway rolling stock and consists in an improved journal box wear plate or pedestal liner.

In railway trucks there is usually provision for relative movement between the box and the pedestal with which the box is assembled, and in some types of trucks the relative movement between these parts is so great that wear on one or the other or both of the parts soon increases the clearance ordinarily provided between the parts to such an extent that the play between the two parts is objectionable.

The main object of my present invention is to provide a simple economical device for preventing wear on the sides of the box or the legs of the pedestal, or, in the event that such wear has taken place, to take up the play thus created.

Additional objects of my invention are to provide in a device of the type referred to means for seating and positioning springs or equalizers or other truck parts usually resting upon the top of the journal box.

In the accompanying drawings illustrating my invention,

Figure 1 is a top view of a box equipped with my improved wear plate.

Figure 2 is in part a side elevation and in part a longitudinal vertical section through the box and wear plate.

Figure 3 is a transverse section through the box, wear plate, and a spring mounted on the box and showing part of the pedestal with which the parts are assembled.

Figures 4, 5, and 6 illustrate a modification of my invention and correspond to Figures 1, 2, and 3 illustrating the preferred structure, no portion of the box or pedestal being shown, and indicating the equalizer bar.

Figures 7, 8, and 9 similarly illustrate a further modification of my invention.

Figures 10, 11, and 12 similarly illustrate another modification of my invention.

Figures 13, 14, and 15 similarly illustrate another modification of my invention.

In Figure 1 the journal box indicated at 1 is of usual construction and is shown with a flat top and flat sides. A relatively thin plate 2 having a general U-shape structure fits over the box, engaging the top and sides thereof, and preferably is provided at front and back with flanges 3 extending at right angles to the body of the plate and adapted to engage the front and rear faces of the

pedestal jaws 4. The portion of the plate which connects the vertical legs is provided with upstanding projections 5 and 6 which serve to center the coil spring 7 carried by the box.

The body of plate 2 forms a seat for spring 7. The lower ends of the vertical legs of the plate are cut away in part to form projections 8 which are bent inwardly and then outwardly as indicated in Figure 3 to provide a yielding clip for engaging the lower corners of the box to retain the plate on the box and prevent any vertical shifting of the plate on the box. These clips would be of special value in the shipment of boxes with plates applied and before they are assembled with the other truck structure.

In the modification illustrated in Figures 4, 5, and 6 the wear plate 9 is adapted to support and position an equalizer bar 10, the underside of the end of which has a groove which is engaged by a corresponding ridge 11 struck up in the top portion of the plate. It will be noted that one or both vertical legs of the plate are cut away as indicated at 12 to clear the adjacent portion of the equalizer.

In the modification illustrated in Figures 7, 8, and 9, the wear plate 13 is adapted to seat and position a leaf spring 14 and is provided with a suitable frame 23 spot-welded to the wear plate at the points W. The frame 23 is rectangular in shape with the sides 23^a at front and back of journal box of such height that they not only position the spring but, in the event of breakage of the spring, they limit the downward movement of the truck frame normally supported by the spring.

Figures 10, 11 and 12 illustrate a modification in which a separate spring seat 15 is mounted upon the wear plate 16 and serves to center the coil spring 17 and decrease the thrust of the same and any wear due to shifting movement of the lower spring coil. This construction permits the provision of a continuous flange 15^a surrounding the lower coil of the spring.

In the modified structure shown in Figures 13, 14, and 15, the wear plate 17 is provided with a slot 18 in its upper portion through which a rib 19 on the box 20 may project and engage a groove in the underface of the end of the equalizer 21. Suitable projections 22 are provided in the wear

plate at each end of slot 18 and serve to position the equalizer lengthwise of the box.

In all of these forms the objects of my invention set forth at the beginning of this

specification are attained, and it will be seen that the provision of my wear plate in the original truck assembly will protect the box and, if the wear plate is made of softer material than the pedestal, will protect the pedestal jaws from wearing, thus eliminating the necessity of providing hardened faces on the pedestal jaws.

When a wear plate is worn out, it may be replaced at a trifling cost compared with the cost of replacing a journal box or pedestal. Due to the slight cost of liner or wear plate replacements, the fit between the journal box and the pedestal may be better maintained and accelerated wear of the parts, which follows increase in the clearance between box and pedestal, may be eliminated.

Various modifications and details of my invention other than those shown by me may be made without departing from the spirit of my invention, and I contemplate the exclusive use of such modifications as fall within the scope of my claims.

I claim:

1. As a new article of manufacture, a one-piece wear plate adapted to be applied to and removed from a standard A.R.A. journal box for railway trucks to prevent contact between the sides of the box and the truck pedestal, said plate including means for engaging the top and both sides and the bottom of the box so that they move together in the pedestal.

2. As a new article of manufacture, a sheet metal wear plate applicable to a standard A. R. A. journal box and adapted to overlie the top and both sides of the box, the front and back portions of said plate being

flanged to engage front and rear faces of a pedestal, and means on said plate for causing it to move with the box to which it is applied.

3. As a new article of manufacture, a U shaped wear plate of sheet metal adapted to straddle an A. R. A. journal box and to overlie the top and both sides of the box and having continuous flanges throughout its length and at right angles to the body of the plate, and having means for engaging the top and bottom of the box.

4. As a new article of manufacture, a U shaped wear plate of sheet metal adapted to straddle an A. R. A. journal box and to overlie the top and both sides of the box, the front and back portions of said plate being flanged to engage adjacent front and rear faces of a pedestal, and the lower ends of said plate being inclined so as to engage adjacent box corners to cause the plate and box to move together in a pedestal with which they are assembled.

5. A U-shaped wear plate adapted to straddle a journal box and overlie the top and sides of the box, each of the ends of the plate being bent inwardly and outwardly to form retaining clips adapted to slip over the top corners of the box and to engage the lower corners of the box.

6. A U-shaped wear plate adapted to straddle a journal box and overlie the top and sides of the box, each of the ends of the plate being cut away for a portion of its extent and the remaining portions being bent inwardly and outwardly to form spaced retaining clips adapted to engage the lower corners of the box.

In testimony whereof I hereunto affix my signature this 17 day of November, 1925.

H. M. PFLAGER.
